UNITED STATES PATENT OFFICE.

WARREN W. BRIGGS, OF PROVIDENCE, RHODE ISLAND.

DESIGN FOR AN ORNAMENTAL CHAIN.

SPECIFICATION forming part of Design No. 12,950, dated May 30, 1882.

Application filed April 24, 1882. Term of patent 7 years.

To all whom it may concern:

Be it known that I, WARREN W. BRIGGS, a citizen of the United States, residing at Providence, in the county of Providence and State 5 of Rhode Island, have invented and produced a new and original Design for Ornamental Chains, of which the following is a full, clear, and exact description, reference being had to the accompanying drawings, forming part of 10 this specification.

Figure 1 is a view of my newly-designed ornamental chain, and Fig. 2 is a side view of the same.

Ornamental chains have heretofore been 15 decorated in a variety of manners, but usually by ornamenting either the links proper or the connecting-links.

The leading feature of my present design consists in a raised band of crescent shape in 20 outline surrounding the connecting-links of the chain.

In the drawings, *a a* are the links proper. *b b* are the connecting-links, and *c c* are the crescent-shaped bands, forming nearly a circle |

and surrounding the connecting-links. These 25 bands may be made of flat stock of the same color or of a different color than the color of the links *a* and connecting-links *b*.

The crescent-shaped bands *c* may be ornamented as shown in the drawings; or they may 30 be made of round or other shaped wire, and may be secured in any desired manner.

The crescent-shaped bands form, in connection with the links and connecting-links, an easily distinguishable new design, and give to 35 the chain a finished and highly-ornamental appearance.

Having thus described my newly-invented design, I claim as new and desire to secure by Letters Patent—

The design for ornamental chains, the same consisting of the crescent-shaped band surrounding the connecting-link of a chain, as 40 herein shown and described.

WARREN W. BRIGGS.
